UNITED STATES PATENT OFFICE

MARIO URBINATI, OF ROME, ITALY

PHASE CHANGING TRANSFORMER

Application filed July 10, 1928, Serial No. 291,663, and in Italy July 25, 1927.

Ordinary transformers, not meant to change the frequency or the number of the phases, act by varying the voltage and the intensity, but they leave unvaried the nature of the transformed current, in the sense that they transform an alternate monophase into another current, likewise alternating monophase current, a triphase current into a triphase current and so on.

10 It is known, however, that in some cases the transformer not only must modify the intensity of the current, and consequently its voltage, but also transform the nature of the current itself, so that the system of currents obtained by the transformation comprises a number of phases different from that of the transformed system.

Cases of this kind occur under various circumstances, more especially in apparatus for 20 the transformation of electric alternate currents into continuous currents, and *vice versa*, which are the subject matter of other applications of mine (Ser. No. 271,572 of April 20, 1928, and Ser. No. 286,953 of June 25 20, 1928), and in which the transformer is so arranged that, besides the transformed fundamental electromotive forces, corresponding to those of the feed system, it furnishes also other additional electromotive 30 forces, whose phases are suitably displaced in respect to the phases of the fundamental forces and are statistically obtained by the composition of electromotive forces, each of which is a fraction of one of the fundamental 35 electromotive forces.

If the number of the additional electromotive forces to be produced is great and their values must meet determinate conditions, considerable difficulties are met with in such 40 transformers in obtaining component electromotive forces the values of which are exactly the fractions required of the fundamental electromotive force.

A particular method to overcome this difficulty has already been indicated in my earlier application Ser. No. 286,953 June 20, 1928.

The said method consists substantially in that only a number of the turns of the secondary winding are wound upon the whole

iron of the core, while the remaining turns surround only a part of the section of the said iron.

When the ratios between the values of the component electromotive forces and the 55 value of the fundamental electromotive forces are simple and not very numerous, the above-mentioned method answers well in practice. It becomes, however, practically insufficient, because it greatly complicates 60 the construction, if the ratios are numerous and the values not simple.

Now, the present invention has just for its object to facilitate in such cases the construction of the transformer, and the desired 65 result is achieved by the adoption of an arrangement which simplifies the relations between the values of the components of the additional electromotive forces and those of the fundamental electromotive forces, also 70 in the case in which the additional electromotive forces are very numerous.

The simplification is substantially obtained by taking advantage, as will be better explained further on, of the following consideration. In a polyphase system of alternating currents all the electromotive forces have the same value; it ensues that if the vectors representing the various phases are arranged with a common origin, they will 75 form a radial diagram, where the free ends of the vectors lie on a circle struck with a radius equal to the common value of the electromotive force of said phases. If it is desired to multiply the number of phases, the 80 vectors representing the additional phases will result equally spaced between the vectors representing the primary electromotive forces, and the free ends of said vectors will lie on the same circle above mentioned. Now 85 if the said additional phases are to be obtained by the combination of two component electromotive forces, said components (which correspond to the coordinates of points of a circumference equidistant between themselves) have, as a rule, relations which are neither rational nor simple in respect of the value of the radius. By abandoning the usual condition of the exact equivalence of 90 the values of the additional electromotive 95 forces, the said components will be such that the radius of the circle will be a rational number, and the 100

forces and of those of the fundamental electromotive forces, resulting in the above mentioned circular radial diagram, it is still possible to form a polyphase system, in which 5 the values of the additional electromotive forces do not materially differ from the value of the fundamental electromotive forces and this notwithstanding that the additional phases are obtained by the combination of components, the values of which are in simple and easily obtainable ratio with the value 10 of the fundamental electromotive forces retaining their ratio very close to the unity, it is possible to obtain a relation of the components and of the fundamental forces that assume simple and easily obtainable values.

Such a variation of the values of the additional electromotive forces could be made empirically in an arbitrary manner, ascertaining 20 for each of them the value most approximate to the exact one, which gives values that are simple in respect to the relation between the components and the fundamental electromotive force.

25 In practice it is possible to proceed in a uniform and systematic manner, assuming as values of the additional electromotive forces the values resulting for them, if in the diagram of the representative vectors, instead of causing the latter to end as is usually the case with their extremities upon a circumference, (fundamental and additional electromotive forces being all equal), they be made to end in points equally distanced on the circumference of a regular polygon, at the vertices of which the vectors of the fundamental currents terminate in the manner shown by the figures of the accompanying drawings, in which

30 Fig. 1 corresponds to the case of the usual polyphase system in which the electromotive forces of the fundamental and the additional phases are all equal and the vectors end in equidistant points of a circumference;

35 Fig. 2 corresponds to the case of the additional electromotive forces the values of which are altered according to the invention, so that the representative vectors have their extremities equally distant on the circumference of a polygon which in the example given in the figure is a hexagon;

40 Fig. 3 refers to the case in which the polygon is a dodecagon, while Fig. 4 shows the arrangement of the secondary winding in a three-phase transformer designed to supply a 24-phase transformed current in accordance with this invention.

45 In the transformers of the abovementioned type is utilized an arrangement similar to that applied in Pacinotti's ring of ordinary dynamos, with the difference that the electromotive forces acting in the various sections of the winding, instead of being produced by the rotation of the ring in an inductive field, are obtained by the static com-

position of the electromotive forces produced in the sections of the secondary windings of a polyphase transformer.

The manner in which this composition takes place has already been explained in my said earlier patent application, and the convenience and utility of the employment of the method herein described will better appear from the consideration of a particular case.

50 Let us consider, for example, a Pacinotti's ring with a collector of 24 bars, at which terminate the extremities of the successive sections of the winding, which generate a system of 24 alternate electromotive forces, 80 all equal among themselves, but whose phases are displaced between each other

$$\frac{360^\circ}{24} = 15^\circ.$$

85 These 24 electromotive forces may be represented, in the plane, by a diagram constituted by 24 vectors having a common point of origin in 0, from which they start radially at equal angular intervals of 15 degrees, 90 ending in 24 points, equidistant among themselves, of a circumference C, described with the centre in 0 and with a radius equal to the value V of the electromotive force between each bar, as shown in Fig. 1.

95 Let us now suppose that it is required to construct a transformer of alternating currents into continuous currents, or *vice versa*, capable of producing 24 secondary phases like those above-mentioned, which are obtained from a triphase current which feeds it, the primary windings being arranged on a three column core.

100 From the secondary windings of the said three columns it is possible to obtain directly the three fundamental electromotive forces together with those opposed to them, namely the forces Fig. 1, represented by the six vectors, 01, 01', 02, 02', 03, 03', whose 105 phases are displaced between each other 60 degrees.

110 In order to complete the desired system of 24 phases, it is necessary to insert 18 other additional phases between the said six fundamental phases, namely three between each two successive ones, as, for instance, those 04, 05, 06 between the two 01, 03', which 115 phases are obtained each by the composition of other two electromotive forces having convenient value and phase.

120 For the sake of a better understanding let us consider the electromotive force represented by vector 05, which finds itself just on the bisecting line of angle 103'. Its two components, as appears in the drawings, are the component 05' and the component 5'5, equal among themselves in value. If, therefore, by V is indicated the value of the electromotive force between two bars, namely 130

the value of the component 05, which is also equal to the radius of circumference C, then we have $05' = 5'5 = 0.577$ V.

In like manner, it would be possible to obtain, for the components of the other phases, fractional values expressed with many decimal figures, and not reducible, as a rule, exactly to simple fractions capable of being expressed in small numbers.

From the foregoing it will appear that, in order to obtain the exact value of the various components, it would be necessary to dispose of a very small value of the volt/turn, or else to have recourse to a subdivision in numerous parts of the core of the column, to obtain the fractions of volt/turn with the method forming the subject matter of my earlier application of June 20, 1928, Ser. No. 286,953.

The object of the present invention is to simplify the construction of the transformer capable of giving the components required for the production of the above mentioned additional electromotive forces inserted among the fundamental ones, and precisely according to this invention, the constructive simplification is obtained by replacing the electromotive forces 01, 04, 05 . . . of Fig. 1, whose terminal points 1, 4, 5 . . . are, as has already been said, distributed at equal intervals on a circumference C, by other electromotive forces 01, 04, 05 . . . whose terminal points 1, 4, 5 . . . are on circumference P of a polygon, which in the case shown in Fig. 2 is a hexagon, but might also be a dodecagon in the case of a couple of triphase transformers, as will be shown later.

It is clear that if points 4, 5, 6 . . . are equally spaced apart on the sides of the polygon, also the corresponding points 4', 5', 6' . . . of the vector 01 will be at equal distances between each other, dividing the vector itself into equal parts, and consequently the components 04', 05', 06' . . . will have values which are simple fractions, expressible in small entire numbers, of the value of the fundamental electromotive force V. And as the other components 6'6, 5'5, 4'4 are identical fractions of 03' namely of the same fundamental force V, it will be seen that all the components are simple fractions of the fundamental electromotive forces.

Moreover, it must be observed that if the side of the polygon is divided by points 4, 5, 6 . . . into n equal segments, it will suffice that the winding of the column comprises mn turns (where m is any entire figure, even=1), in order that each component be given by an entire number of turns.

In consequence of the aforesaid modification of the diagram, from the radial-circular to the radial-polygonal shape, the value of the successive electromotive forces is no longer constant, and also the angle of phase difference is no longer exactly constant; but

the small variations which take place are not such as to impair the working of the transformer, and they are all the more negligible, the greater the number of the sides of the polygon. On the other hand, it is possible to obtain the very great advantage that the ratio between the values of the components of the inserted electromotive forces and the common value V of the fundamental electromotive forces becomes very simple. In the aforesaid case just examined, for instance, and illustrated in Fig. 2 of the drawings, the components of the electromotive force 04 are respectively $04' = \frac{3}{4}$ V, and $4'4 = \frac{1}{4}$ V; the components of the electromotive forces 05 are $05' = 5'5 = \frac{1}{2}$ V etc.

This simplicity of relations is accompanied by a corresponding constructive simplicity; if, for example, the fundamental electromotive force is obtained by a winding of 8 turns, 04' will be obtained with 6 turns, 4'4 with 2 turns and so on.

In Fig. 4 is shown the arrangement of the secondary windings in a three-phase transformer for obtaining the 18 additional phases corresponding to the 18 electromotive forces inserted between the three fundamental ones 01, 02, 03 and their opposites 01', 02', 03', as shown in the diagram of Fig. 2. For the sake of clearness, only those sections of the secondary windings are shown which correspond to the components of the electromotive forces 04, 05, 06 inserted in the sector 103', it being understood that the construction is identically repeated for the additional electromotive forces of the other sectors.

The three cores of the transformer, whereon are arranged the primary windings p_1 , p_2 and p_3 corresponding to the three phases of the feeding current supplied by the three-phase line 1, are indicated by 1, 2, 3. In order to obtain the five electromotive forces 01, 04, 05, 06, 03' of the diagram, Fig. 1, four sections of the secondary winding are placed on each of the two cores 1, 3 and wound in opposite directions. The four sections 01, 04', 05', 06' placed on core 1 comprise respectively 4, 3, 2 and 1 whole turns, while the four sections 4'4, 5'5, 6'6, 03' placed on core 3 comprise respectively 1, 2, 3 and 4 turns.

The free ends of the section 01 on core 1 are connected by means of the wires g , h to the bars a , b of a fixed collector C. The sections 04', 05', 06' of core 1 are connected in series respectively with the oppositely wound sections 4'4, 5'5, 6'6 of core 3 and the ends n p , p q , q r of each of said pairs of sections are respectively connected by means of the wires h i , i j , j k to the bars b c , c d , d e of the same collector C. Finally, the section 03' of core 3 is connected to the bars e f of the collector. It will thus be seen that the bars a b , e f correspond respectively to the fundamental electromotive forces 01, 03', while the bars b c , c d , d e correspond respectively

to the additional electromotive forces 04, 05, 06 obtained by the combination of 04' with 4'4, 05' with 5'5, 06' with 6'6.

The stationary collector rests on an insulating ground plate G, and against the collector are mounted the two rotating brushes n_1 and n_2 , which by means of connections not shown on the drawings are respectively electrically connected to the revolving rings d_1 d_2 upon which rest the collecting brushes f_1 f_2 which collect the direct current. The brushes n_1 and n_2 are driven by the synchronous motor M which is also fed by the current of the three phase line 1.

A noteworthy simplicity of construction results from the fact that the fundamental as well as the additional electromotive force are obtained by a whole number of turns of the secondary windings, and that the total number of turns of the sections connected in series to form an additional electromotive force is constant and equal to the number of turns of the sections of the secondary windings supplying the fundamental electromotive forces and their opposite ones. This characteristic can be read geometrically on the diagram of Fig. 2.

From the above it appears that generally speaking (apart from the device for the partial reduction of the section of the core in accordance with the method forming the subject matter of my earlier application of June 20, 1928 Ser. No. 286,953), in the case of a three column transformer it may be said that if it is desired to have a secondary winding with number $6n$ of phases, namely with n phases comprised in each angle of 60 degrees, it will suffice that the number representing V, that is the value of one of the fundamental electromotive forces, be a multiple according to n of the value of the volt/turn, that is to say that there be the relation $V=s n$, indicating by s the value of the volt/turn; in other words, it will be sufficient, that the said number be the value of the volt/turn $s=V/n$, or a submultiple of this value $s=V/nm$.

If, instead of one transformer alone, there are available two transformers, from which it is possible to derive directly 12 fundamental electromotive forces whose phases are displaced 30 degrees relative to each other, it will be possible to construct for the fundamental vectors a radial diagram, wherein the terminal points of the electromotive forces fall on the circumference of the dodecagon.

Fig. 3 represents the case of a secondary winding with 60 phases, namely with 5 phases every 30 degrees. The 12 fundamental electromotive forces are those 01, 02, 03 ... corresponding to the vertices of the polygon, and whose phases are displaced 30 degrees one in respect to the other. The arrangement and the connection of the sections of the secondary windings on the cores are the same as in the case of the transformer shown in Fig. 4.

Although in the preceding explanations has been particularly considered the case of the transformation of a three-phase current, it is clear that the same method is applicable to polyphase currents of another kind, and although, for simplicity's sake, has been considered the variation of the values of the inserted electromotive forces which carry the extremities of the corresponding vectors from a circumference to the circumference of a regular polygon therein described, it is also possible to act in such manner that the values of the additional electromotive forces are individually varied only so slightly as is sufficient to reduce their components in such a way as to have simple values with the fundamental electromotive force, always obtaining a good working of the transformer.

It is also understood that, although in the specification and in the drawings only symmetrical arrangements have been considered, nevertheless the method allows to obtain, when required, asymmetrical arrangements of the vectors and of the systems of electromotive forces transformed into whatever number desired, which number may even not be a multiple of that of the fundamental electromotive forces.

I claim:

1. In transformers for polyphase currents of the type which being fed by a system of alternating currents comprising n primary phases transform it into a system of alternating currents comprising $n m$ phases, the combination of n cores, n primary windings one for each of said cores through which circulate the n alternating currents of the feeding system, n secondary windings each comprising m distinct and separated sections, each section comprising a whole number of turns changing gradually in the successive sections in such a manner that all the numbers are of the form $k p$, in which k is an integer varying from l to m and p the number of the turns of the smallest of the sections.

2. Transformers for polyphase currents as specified in claim 1, including means for connecting in series the sections of the secondary windings of each two cores in such a manner that the sum of the number of turns of each pair of sections connected together always results equal to mp , a collector, and means for connecting the bars of the collector with said pairs of sections and with the sections, one on each core, the number of turns of which is also mp , the arrangement being such that by tapping the currents delivered at the bars of the collector, a system of electromotive forces is obtained so interrelated that the diagram of the corresponding vectors is a radial one with the ends of the vectors distributed at equal distances on the sides of a regular polygon.

3. In transformers for polyphase currents of the type which being fed by a system of

alternating currents comprising n primary phases transform it into a system of alternating currents comprising $2nm$ phases, the combination of n cores, n primary windings, 5 one for each of said cores, through which circulate the n alternating currents of the feeding system, n secondary windings each comprising $2m$ distinct and separated sections, m of the said sections being wound in the 10 opposite direction of the other m , each section comprising a whole number of turns, changing gradually in the successive sections of each set wound in the same direction in such a manner that all the numbers are of the 15 form $k p$, in which k is an integer varying from l to m and p the number of turns of the smallest of the sections.

4. Transformer for polyphase currents as specified in claim 3 including means for connecting in series the oppositely wound sections of the secondary windings of each two cores in such a manner that the sum of the number of turns of each pair of sections connected together always result equal to mp , a collector, and means for connecting the bars of the collector with the said pairs of sections and with the sections, two oppositely wound on each core, the number of turns of which is also mp , the arrangement being such that 20 by tapping the currents delivered at the bar of the collector, a system of electromotive forces is obtained so interrelated that the diagram of the corresponding vectors is a radial one with the ends of the vectors distributed 25 on each core, the number of turns of which is also mp , the arrangement being such that 30 at equal distances on the sides of a regular polygon.

In testimony whereof I have affixed my signature at Rome, Italy, this 26th day of June, 1928.
